UNITED STATES PATENT OFFICE.

RALPH BARGER, OF FRANKFORT, NEW YORK, ASSIGNOR TO REMINGTON ARMS COMPANY, INC., A CORPORATION OF DELAWARE.

FIREARM.

Application filed September 11, 1924, Serial No. 737,035. Renewed November 19, 1927.

This invention relates to firearms and is particularly adapted for use on firearms of the type shown in the Patents 719,955, Feb. 3, 1903, and 789,755 May 16, 1905, to John D. Pedersen. These patents disclose a firearm of the magazine type, particularly adapted to accommodate shot shells. Such shells or cartridges are loaded into a tubular magazine from the rear end thereof, and are retained therein by a stop or lug consisting of a stiff spring attached to the "carrier". As the forearm and action bar are retracted in the operation of loading the gun, the carrier is rotated to release the rearmost cartridge from the stop, said cartridge then slides rearwardly onto a suitably constructed part of the carrier. On the forward movement of the action bar the carrier is usually rotated to elevate the cartridge into alignment with the chamber, and the stop lug is thereby brought into position to engage the base of the next cartridge. The lifted cartridge is pushed into the chamber by the breech block. The firing pin and cocking head were retracted on the rearward movement of the action bar, and as the action bar and breech block reach their final forward positions the action bar is locked against another rearward movement until the hammer has moved forward to fire the shell in the chamber.

In this gun as hitherto constructed, in order to remove shells from the magazine without firing them, it has been necessary to release the action bar lock by means provided for this purpose, and to repeatedly operate the action bar, each shell in turn passing through the same series of movements as though it had been fired, or by careful manipulation each shell may be removed from the position in which it is elevated into line with the chamber but has not yet entered the chamber. This necessity arose from the fact that shells were retained in the magazine by a latch of such construction that it could not be readily displaced. Even the operation of loading the magazine was difficult owing to the necessity for forcibly displacing this semirigid latch member.

One object of this invention is to provide an improved means for retaining shells or cartridges in the magazine.

A further object of this invention is to

provide means whereby shells or cartridges may be removed directly from the magazine without operating the action bar.

A further object of the invention is to provide an improved cartridge or shell stop which can be manually moved to ineffective position, thereby permitting the removal of the shells in the magazine.

With these and other objects in view my invention consists in the novel combinations and arrangement of parts hereinafter described and illustrated in the drawings.

In said drawings Fig. 1 is a vertical longitudinal section through the receiver of a firearm embodying my invention.

Fig. 2 is a horizontal section on the line 2—2 of Fig. 1.

Fig. 3 is a perspective of my improved shell carrier and stop showing this member in engagement with the head of a shell.

The receiver 10 which encloses the main parts of the operating mechanism, has an opening 11 at the bottom to permit of loading and ejecting the shells. The breech block 12 when at the limit of its forward movement engages a recoil shoulder 13 on the receiver frame, locking the breech block against rearward movement until released from said shoulder. The breech block is recessed to receive a firing pin 14, inserted therein from the rear, and terminating at its rear end in a cocking head 15 comprising a shoulder 16 adapted to be engaged by a sear 17, which is held in engagement with shoulder 16 by a sear spring 18. The sear comprises a laterally extending foot 19 which extends under the forward end of the trigger 20.

The breech block is adapted to be reciprocated thru its connection with a forearm 21, which encircles a magazine 22 adapted to receive a column of cartridges. The forward cartridge in said column engages the plunger which is pressed rearwardly by spring 24. The means for retaining shells in the magazine and for transferring them one at a time from the magazine to position to be pushed into the chamber by the breech block, will now be described.

A carrier comprising a spindle 25 having a wing or blade 26 rigid therewith, lies in a longitudinal recess in the wall of the receiver 10, and is journaled in the ends of said recess for rotation about a longitudinal

axis. Integral with the spindle 25 near its rear end is a spiral cam follower 261, adapted to engage a cam groove in the breech block. Fixed to the carrier is a guide lug 27 which forms a lower support and guide for the breech block during the major part of its movement. Pivoted on the carrier near its forward end is a shell stop or latch 28, adapted when said carrier is in normal position, to retain the shells in the magazine by engaging the head of the rearmost shell. Said latch 28 is pressed toward effective position by a spring 29, interposed between the carrier and the rearward end of the latch.

Rigid with spindle 25, somewhat forward from the latch 28 and angularly disposed relative thereto, is a second stop or temporary catch 30, adapted to engage the base 20 of the rearmost shell in the magazine and temporarily retain the shells when the carrier is rotated so that latch 28 is ineffective for this purpose, as will be presently explained. The operation of the carrier is as 25 follows:

When the breech block is forward the carrier blade 26 stands vertically at one side of the breech block, in a recess in the receiver wall. As the breech block moves 30 rearwardly the carrier remains in this position while the shell in the chamber is extracted and ejected downward past the carrier by the spring pressed ejector 31. After this has occurred, and very near the end of 35 the rearward movement of the breech block the carrier is rotated by the engagement of spiral cam 261 with a suitably shaped part of the cam groove 262 on the breech block. This movement places the carrier blade sub- 40 stantially transversely of the receiver, in which position it is adapted to receive the shell to be released from the magazine. Near the end of the carrier movement the pivoted stop or latch 28 moves laterally off the head 45 of the rearmost shell, which shell under the pressure of the magazine spring 29 moves back onto the carrier, the next cartridge in front being stopped by temporary catch 30. As the breech block begins to move forward 50 the carrier is reversely rotated, lifting the shell thereon into alignment with the chamber. The carrier does not return at once to its normal inactive position in the recess in the receiver wall, but remains in a position 55 in which it supports the shell between the breech block and the chamber while the breech block advances and begins to slide the shell into the chamber, the controlling cam groove 262 on the breech block being suit- 60 ably shaped for this purpose. At the proper time the carrier returns to inactive position, the rearmost shell in the magazine resting against the latch 28, and the cycle of operation is complete.

65 My invention renders it possible to unload

the magazine without operating the action bar at all. The shells in the magazine are retained solely by latch 28, which latch is held in effective position by a comparatively light spring 29. Latch 28 can, therefore, be 70 manually retracted at will to release the rear-most shell, which shell is then removed, and the operation repeated for each shell in the magazine. The pivotal mounting of this latch also permits its ready deflection in 75 loading the magazine.

The invention is not to be considered as limited to the precise construction herein described and illustrated in the drawings, but is to be construed as covering all equivalent 80 devices falling within the scope of the appended claims.

I claim:

1. In a magazine firearm, a cartridge transferring means comprising a member rotatable about an axis parallel to the length of the firearm, a cartridge stop member pivoted to said cartridge transferring member, and yielding means for retaining said cartridge stop member in effective position. 85

2. In a firearm comprising a magazine, a receiver, a chamber, means for transferring cartridges from said magazine through said receiver to said chamber comprising a carrier which normally occupies a recess in the side of the receiver, and is rotated about a longitudinal axis to move cartridges into line with said chamber, a cartridge stop member pivoted to said carrier and adapted to retain cartridges in said magazine when said carrier is in normal position and yielding means normally effective to hold said cartridge stop member in effective position. 95

3. In a firearm, cartridge transferring means comprising a carrier mounted for rotation about a longitudinal axis; a cartridge retaining stop on said carrier adapted to release the cartridge retained thereby on rotation of said carrier, said cartridge retaining stop being adapted to be manually moved to ineffective position without movement of the carrier. 105

4. In a firearm comprising a breech closing block and a magazine adapted to contain cartridges in column, means for retaining cartridges in said magazine comprising a pivoted cartridge stop adapted to be manually moved to permit the removal of cartridges from said magazine while said breech block is in breech closing position. 115

5. In a firearm comprising a magazine, a chamber and means for transferring cartridges from the magazine to the chamber and a chamber closing breech block, a stop normally retaining cartridges in said magazine having a translational movement for permitting the transfer of cartridges from the magazine to the chamber and a rotational movement for permitting the withdrawal of cartridges from said magazine 125 130

independent of the cartridge transferring means while the chamber is closed by the breech block.

6. In a firearm comprising a breech closing block and magazine adapted to contain a column of cartridges inserted therein from the rear, means for permitting the manual

withdrawal of said cartridges one at a time from said magazine when said breech block is in breech closing position comprising a ¹⁰ pivoted stop adapted to engage the head of the rearmost cartridge and to be manually moved to ineffective position.

RALPH BARGER.
